METHOD OF LAYING SHEET METALLIC FLOORING

Walter G. Koch, Evansville, Ind., assignor to International Steel Company, Evansville, Ind., a corporation of Indiana

Application January 6, 1949, Serial No. 69,525

3 Claims. (Cl. 29—148.2)

1

My invention relates broadly to transportation equipment and more particularly to a construction of sheet flooring and method of laying the same in transportation units.

One of the objects of my invention is to provide an improved method for installing a floor in transportation units for sanitary transportation of meats, fruits, vegetables, and other commodities to the markets.

Another object of my invention is to provide a method of laying a metallic flooring for transportation units in large sheets in coaction with the side walls of the transportation unit for providing a sanitary interior for the transportation unit.

Other and further objects of my invention reside in an improved method of installing the stainless steel flooring, as set forth more fully in the specification hereinafter following by reference to the accompanying drawings in which:

Figure 1 is a horizontal view taken on line 1—1 of Fig. 2 showing the interior of a transportation unit with the metallic flooring of my invention installed therein; Fig. 2 is a longitudinal sectional view taken on line 2—2 of Fig. 1; Fig. 3 is a detail transverse sectional view of one of the metallic floor sheets on a scale enlarged with respect to the scales of Figs. 1 and 2; Fig. 4 is a fragmentary view on an enlarged scale illustrating one method of forming a butt weld between adjacent metallic floor sheets, the upstanding sides of the metallic floor sheets being illustrated in longitudinal section; Fig. 5 is a fragmentary sectional view taken on line 5—5 of Figs. 1 and 4; Fig. 6 is a fragmentary plan view of a modified form of connection for the metallic floor sheets forming the floor in which adjacent floor sheets have their transverse edges interconnected, overlapped and spot welded; Fig. 7 is a fragmentary longitudinal sectional view taken on line 7—7 of Fig. 6, and extended to include an entire floor sheet; Fig. 8 is a fragmentary sectional view of two sections of flooring connected by a butt weld and prepared for an overlapping connection at one end as used in the form of my invention illustrated in Fig. 7; Fig. 9 is a schematic view illustrating my improved method for installing a large area of flooring in a transportation unit, the view illustrating the position of the section of flooring as it is introduced into the top of the transportation unit; Fig. 10 illustrates the manner of automatically releasing the section of flooring as it comes to rest on the base structure of the transportation unit, the view being taken on line 10—10 of Fig. 11; Fig. 11 is a horizontal

2

sectional view taken on line 11—11 of Fig. 10 illustrating the rig employed for installing the metallic floor sections; Fig. 12 is a perspective view illustrating the method of overlapping the metallic flooring at one end of the transportation unit and Fig. 13 shows the manner of overlapping the metallic sheet flooring adjacent the door opening of the transportation unit.

My invention is directed to an improved method of laying metallic flooring. My invention is illustrated as applied particularly to refrigeration cars but it will be understood that my invention is equally applicable to trucks and other mobile carriers.

15 When my invention is applied to refrigeration cars, wide strips of flexible stainless steel are welded edge to edge to form a flexible floor of large area for covering approximately one-half of the interior of the refrigerator car. The 20 stainless steel flooring constituted by the several transversely extending strips has resilient side wall extensions formed integrally therewith. These side wall extensions are angularly displaceable in a sidewise direction as the central portion of the sheet flooring is displaced in a vertical direction. Accordingly, I provide a rig 25 having transversely extending pintles slidably engageable through transversely aligned apertures in the side wall extensions of the flooring in such manner that the sheet flooring may be suspended and maintained on the rig while it is being introduced and moved into position into the transportation unit and then automatically released when the flooring comes to rest on the base of the transportation unit or car in its required position. Thus large areas of flooring may be rapidly and uniformly laid in each of the halves of a refrigerator car and a highly sanitary lining for the car quickly installed.

30 Referring to the drawings which will be described as applied to a refrigeration car, reference character 1 designates the conventional floor for a refrigerator car having side walls 2 and 3 and end walls 4 and 5. The conventional space for refrigeration units is provided in each 35 end of the refrigerator car as represented at 6 and 7 with partitions 8 and 9 separating the refrigeration units from the interior of the refrigerator car. The sanitary flooring comprises a multiplicity of wide strips of stainless steel formed in two units laid in opposite ends of the refrigerator car. The unit in one end of the refrigerator car comprises transverse strips 11, 12, 13, 14, 15 and 16. The unit in the other end of the refrigerator car comprises transverse strips

17, 18, 19, 20, 21 and 22. The end strip in each instance has an outwardly projecting end portion represented at 11a and 22a respectively, which extend beneath partitions 8 and 9 and overlap the extended edge 50 of the drip pan 51 installed in each of the refrigerator unit spaces 6 and 7 in each end of the refrigeration car. All of the other strips, as well as the strips 11 and 22, have upwardly extending side portions represented at 11b, 11c; 12b, 12c; 13b, 13c; 14b, 14c; 15b, 15c; 16b, 16c; 17b, 17c; 18b, 18c; 19b, 19c; 20b, 20c; 21b, 21c; and 22b, 22c.

The several strips are interconnected at their transverse edges so that each unit forms a substantially continuous plane area. Several methods may be employed in forming the seams between the transversely extending edges of the several strips. One method is illustrated in Figs. 1 and 5, where strips 14 and 15 are butt welded at their adjacent transverse edges, as represented at 23, and the transverse edges welded in a fluid-tight joint. In Figs. 6 and 7, I show a modified form of connection wherein the strips are overlapped. For this purpose the transverse strip 14 has its trailing edge slightly displaced upwardly as represented at 14d, while the leading edge of the co-acting adjacent strip 15 is displaced slightly downwardly as represented at 15d, so that the adjacent strips telescopically fit one into the other. This same deformation exists with respect to the side walls 14c and 15c of the adjacent strips as represented in Fig. 6 where the upstanding edge 14c' extends slightly inwardly while the upstanding edge 15c' extends slightly outwardly allowing a slight overlap of the edges of the transverse strips 14 and 15 for thus forming a floor and side wall surface which is substantially continuous.

In order to explain the manner of establishing the seams between the adjacent transverse strips, I have greatly exaggerated the displacement of the seamed edges at the scale on which Figs. 4-8 have been drawn, and it will be understood that in practice the seam at the overlap is scarcely perceptible and a substantially plane surface is provided. In order to assure the covering of the car floor in a substantially continuous plane with minimum bulge at the seams between the strips, I may connect the strips by the transverse butt weld as heretofore explained in connection with Figs. 1-5. In this arrangement co-acting adjacent strips 14 and 15 have their transverse edges aligned and united by a butt weld along the zone indicated at 23. This butt weld extends continuously throughout the bottom central portion of the transverse strips as well as the upstanding end portions 14c and 15c, shown in Fig. 4.

In Fig. 8 I have shown a composite method of connecting the floor strips by providing for a butt weld at 23 and an overlap connection and welded seam at 24. The displaced end 24 coacts with a complementary-shaped portion of an adjacent strip.

The plane metallic floor surface thus constructed, when installed in the refrigerator car, provides a continuous sanitary surface extending from opposite ends of the refrigerator car to the loading and unloading section of the car at the center thereof, represented at 25 in Figs. 1, 2 and 11. The center of the refrigerator car is shown as provided with conventional refrigerator doors 26 and 27. The central loading and unloading zone 25 is provided with a stainless steel floor section 28 which is lapped under or butt welded to the transverse edges 16e and 17e of strips 16 and

17. The stainless steel threshold plate 28 insures a continuous flow of washing fluid for cleaning the refrigerator car. The metallic surface is thus substantially continuous throughout the threshold of the refrigerator car.

In order that the joint at each corner of floor section 28 and the car wall shall be tight, I provided a corner closure angle strip 52 having horizontally extending foot portions 53 and 54 extending at right angles thereto and projecting beneath the floor section 28 and floor section 17 which has an upstanding side wall welded at some spots 17h to the strip 52. At the opposite end of the flooring where connection is made to the drip pan 51 as shown in Fig. 12 a closure plate 55 is provided shaped to conform with the base structure 1 and with the drip pan 51. The corner closure plate 55 laps under floor section 11 at 56 and laps over drip pan 51 at 57 and 58. A welded connection may be made along the edge of side wall 11b at 11h as indicated.

Fig. 3 is a transverse sectional view taken through one of the transverse strips, such as strip 14, and illustrating the central bottom portion and the upwardly extending side portions 14b and 14c. The stainless steel sheet constituting the transverse strip 14 is flexible and resilient and the side portions 14b and 14c are integrally connected therewith so that vertical displacement of the central portion 14 is accompanied by angular displacement of side portions 14b and 14c. The side portions 14b and 14c are biased outwardly by the inherent resiliency of the material of the strips. This property of each of the transverse sheets when assembled into the unit of large area for filling each of the interior ends of the refrigerator car facilitates the installation of the floor units. This will be clear from a consideration of Figs. 9-11.

In Fig. 9 I have shown the body structure of the transportation unit disposed beneath the track or runway 30 supported on columns 31 and 32 and carrying traveling crane 33. The traveling crane 33 supports the hoist 34 which may be raised and lowered under control of chain system 35. In Fig. 9 I have shown the hoist near its extreme upper position connected with the longitudinally extending beam 36. Flexible chains 37 extend from beam 36 and connect with angle members 38, 39, 40 and 41 which extend parallel to central beam 36 and serve as supports for the transverse beams 42, 43, 44 and 45. Transverse beams 42 and 43 are suspended from one end of longitudinally extending beam 36, while transverse beams 44 and 45 are suspended from the other end of longitudinally extending beam 36. The suspension of both sets of beams is symmetrical and both sets of beams pendently hang in a position for supporting the metallic floor unit.

The transverse beams 42, 43, 44 and 45 each have their opposite ends shaped to provide engaging pintles, that is, end sections of small diameter resembling horizontally extending pins which I have designated at 42a, 42b; 43a, 43b; 44a, 44b; 45a, 45b. The tip to tip transverse distance from pin 45a to pin 45b is shorter than the interior width of the transportation unit between walls 2 and 3, so that the rig including the transverse beams may be readily lowered into the interior of the transportation unit as represented in Figs. 9, 10 and 11.

The floor units are provided with sets of perforations in positions adapted to register with the termini of the several pins on the opposite ends of the transverse beams 42, 43, 44 and 45.

That is to say, transverse strip 11 is provided with centrally disposed perforations 11f and 11g in the outstanding end portions 11c and 11b. Similarly, transverse strip 13 is provided in the opposite ends 13c and 13b thereof with centrally arranged perforations 13f and 13g, whereby pins 42a and 42b of beam 42 may be aligned with perforations 11f and 11g, while pins 43a and 43b are aligned with perforations 13f and 13g, respectively. In a similar manner pins 44a and 44b of transverse beam 44 may be aligned with perforations 14f and 14g in end portions 14c and 14b of strip 14. At the same time pins 45a and 45b may be aligned with perforations 16f and 16g in the ends 16c and 16b of strip 16. With the rig thus aligned the sheet metal floor unit may be hooked over the ends of the pins and the floor unit supported on the rig as represented in Fig. 9, ready for lowering into the bottom of the transportation unit.

The mass of the average floor unit for conventional refrigerator cars constructed in accordance with my invention averages approximately 600 lbs. and of a length of approximately 15' and an overall transverse width of approximately 8' 6 $\frac{3}{4}$ ". The stainless steel flooring I employ is U. S. Standard #18 gauge having a thickness of approximately .0375", and as the floor unit gravitates downwardly as represented in Fig. 9 which is a transverse cross sectional view through the floor unit, as represented for example by strip 16, the ends 16c and 16b are eanted inwardly whereby the perforations 16f and 16g engage over the pins 45a and 45b. In this position there is sufficient clearance for the floor unit to be lowered between the interior side walls 2 and 3 of the transportation unit. The fact that the floor unit gravitates downwardly under its own mass along a longitudinal center line effects a contraction in the effective transverse width of the floor unit. In this way the floor unit is lowered into position in the direction of the arrow 46 in Fig. 9 to a position in which the lowermost portion of the catenary formed by the floor unit strikes the longitudinal center line of the car body shown at 1 in Fig. 10. As the rig continues its downward descent the flexible resilient sheet-like material of the flooring flattens downwardly against the surface of the base structure of the transportation unit 1 serving to automatically shift the side portions represented at 16c and 16b outwardly toward the interior of the walls 2 and 3 of the transportation unit as limits, whereby perforations 16f and 16g are freed from the ends of pins 45a and 45b. This serves to automatically release the rig 36 leaving the flooring unit properly centered in the transportation unit. The rig is then free to be withdrawn from the transportation unit ready for the connection thereto of another floor unit for a subsequent floor placement operation. The approximately 600 lbs. of resilient and flexible sheet metal flooring is thus laid in position ready to be secured to the side walls of the transportation unit. Fig. 10 shows an exaggerated inclination of the side portions 16c and 16b in order to illustrate the principle involved as the side portions orient toward the side walls.

Wherever in the claims I have mentioned seaming of the flooring strips I intend the term seamed to include welding or connecting generally.

The floor of my invention provides a usable structurally hard metallic surface for wear under severe loading conditions. In laying the floor-

ing a layer of mastic may be spread on the flooring for adhesion of the hard metal flooring to the wood structural floor. Any desired form of sheet flooring may be laid on the structure.

I have found the floor construction of my invention highly practical in use in rendering the interior of refrigerator cars clean and sanitary and ready to be washed out and cleansed after use. The method of laying the floor has been found to be very practical and saving in time and labor. I realize however that modifications might be made and I desire that it be understood that I intend no limitations be made upon my invention other than may be imposed by the scope of the appended claims.

What I claim as new and desire to secure by Letters Patent of the United States, is as follows:

1. The method of laying a sheet of substantially flat metallic flooring in a restricted space which consists in bending opposite sides of a flat metallic sheet of flooring upwardly, perforating the upwardly bent sides at spaced intervals along the length thereof, suspending the metallic sheet from the perforations in the bent sides, centering the suspended sheet over a confined area in which the sheet of flooring is to be deposited on a base, lowering the flooring through the confined area while the flooring gravitates downwardly at its center along a catenary curve, resting the curved portion of the flooring on a base support, and laying the co-extensive portions of the sheet on the base support while imparting an outwardly flexing bodily movement to the sides of the sheet for freeing the perforations thereof from the suspensions.

2. The method of installing a sanitary metallic floor for transportation units which comprises seaming a multiplicity of transverse strips of metallic sheeting appreciably longer than the width of the transportation unit aggregating in length approximately one-half the length of the transportation unit, perforating the marginal edges of the strips, suspending the transverse edges of the strips from the perforations therein to form a central catenary curve and effecting a contraction in the overall length of the strips to a length capable of passing through the confined area of a transportation unit, resting the central catenary curve portions of the strips on the bottom of the transportation unit and releasing the strips for establishing contact between the marginal edges of the strips and the side walls of the transportation unit and throughout the area of the bottom of the transportation unit.

3. The method of covering the interior of the base and portions of the side walls of a transportation unit with metallic sheeting having a transverse dimension appreciably in excess of the width of a transportation unit and a length sufficient to cover approximately one-half of the interior length of the transportation unit, perforating the marginal edges of certain of the metallic strips, forming upstanding end portions on the ends of the strips, suspending the metallic sheet at spaced positions transversely thereof from the perforated marginal edges thereof for contracting the sheet to a distance effectively less than the width of the transportation unit for passing the sheet through the open top of the transportation unit, lowering the metallic sheet through the transportation unit with the marginal edges extending upwardly in tension and the central portion of the

sheet lowered downwardly in a catenary curve, resting the lowered portion of the sheet against the base of the transportation unit and releasing the metallic sheet from the edge suspension thereof when the lowered portion of the metallic sheet rests upon the base of the transportation unit throughout substantially the entire area of the sheet for forming a substantially continuous metallic covering over approximately one-half of the effective length of the transportation unit, and providing a side wall lining upwardly at opposite side walls thereof.
